UNITED STATES PATENT OFFICE

118,953

DESIGN FOR A TOY AIRPLANE

Lyle Thro, Minneapolis, Minn., assignor to General Mills, Inc., a corporation of Delaware

Application November 17, 1939, Serial No. 88,334

Term of patent 3½ years

To all whom it may concern:

Be it known that I, Lyle Thro, a citizen of the United States, residing at Minneapolis, in the county of Hennepin and State of Minnesota, have invented a new, original, and ornamental Design for Toy Airplane, of which the following is a specification, reference being had to the accompanying drawing, forming part thereof.

In the drawing

Fig. 1 is a perspective view of a toy airplane, showing my new design;

Fig. 2 is a top plan view;

Fig. 3 is a bottom plan view, and

Fig. 4 is a front elevation.

I claim:

The ornamental design for a toy airplane, as shown.

LYLE THRO.
